KEMPTON ADAMS, OF REDDING RIDGE, CONNECTICUT

MIXER

Application filed June 21, 1928, Serial No. 287,181. Renewed January 6, 1930.

This invention relates to mixing apparatus and particularly to a machine or apparatus for mixing materials, such as the ingredients of concrete.

5 The modern tendency in concrete practice is to use a stiff mix and mechanical devices or mixers now on the market are not adapted for or suited to the present requirements. Furthermore, difficulty has been experienced 10 in effecting the complete discharge of the material from mixers of the type specified. This invention has for its salient object to provide a mixer adapted for thoroughly and efficiently stirring and working the ingredients of a stiff or relatively dry mix.

Another object of the invention is to provide a mixer so constructed and arranged that the mixed materials can be quickly, positively and completely discharged from the apparatus.

20 Further objects of the invention will appear from the following specification taken in connection with the drawings, which form a part of this application, and in which Fig. 1 is a vertical sectional elevation of a mixer constructed in accordance with the invention; and

25 Fig. 2 is a top plan view of the structure shown in Fig. 1.

30 The invention briefly described consists of a receptacle having deflecting means therein and a member centrally disposed in the receptacle and also having vanes adapted to contact with the receptacle vanes in thoroughly 35 intermixing the material in the receptacle.

35 Means is provided for rotating the receptacle and the centrally disposed member in opposite directions and for reversing the direction 40 of rotation of these parts. The centrally disposed member carries the closure for the discharge opening of the receptacle and is so mounted and driven that the rotation of the parts in one direction will open the closure 45 and the rotation of the parts in the other direction will close the closure. Furthermore, the closure is so connected to the centrally disposed member that the rotation of the member will not cause the corresponding rotation of the closure.

Further details of the invention will appear from the following description.

In the form of the invention illustrated, the mixer consists of a receptacle 10 having an annular flange 11 extending laterally therefrom and supported on a plurality of rollers 12 carried by a ring 13 which in turn is supported on vertical frame members or posts 14 and 15.

55 The receptacle 10 also has mounted on its outer surface a plurality of vertically disposed rollers 18 which engage an annular guide-rail 19 carried by the frame members 14 and 15. The upper end of the receptacle has secured thereto a ring 20 having an upwardly extending flange 21 within which are disposed a plurality of rollers 22 mounted on vertical axes and carried by an annular frame 23.

60 The receptacle 10 has secured thereto on its outer surface, a gear 25, and the annular frame 23 has also secured thereto at the upper end thereof, a gear 26.

65 A plurality of deflecting blades or vanes 30 and 31 are mounted on the inner surface of the receptacle and are adapted to deflect the material being mixed inwardly and upwardly and to turn the material over.

70 The annular frame 23 has secured thereon and extending diametrically thereof, arms 35 and 36 which in turn have an annular ring 37 formed at the inner ends thereof. The ring 37, as shown in Fig. 2, is split, the two halves being secured together by flanges 38 and clamping bolts 39. The inner surface of 75 the ring 37 is provided with coarse screw threads 40 and the threaded upper end 45 of a cylindrical post 46 is mounted in the ring 37. The outer surface of the upper threaded portion of the cylindrical post 46 has secured thereto a pair of stop lugs 48 and 49.

80 The lug 48 is adapted to engage a lug 50 carried by the upper end of the ring 37 and the lug 49 is adapted to engage a lug 51 secured to the lower surface of the ring 37.

85 The receptacle 10 has a discharge opening 55 at the lower end thereof adapted to be closed by a closure 56 carried by a post or rod 57. The upper end of the rod has secured thereto a disk 58 which is positioned 90

95

within the cylindrical post 46. A disk 59 is fixedly secured in the lower end portion of the cylindrical post 56 and a spring 60 is interposed between the disk 59 and a disk 61 which is positioned below the disk 58. The adjacent surfaces of the disks 58 and 61 are grooved and have positioned therebetween balls 62.

From the foregoing description it will be seen that the spring 60 tends to hold the closure in engagement with the closure seat or inner surface of the opening 55, when the cylindrical post 46 is disposed in the position shown in Fig. 1. It will also be clear that the post 46 can rotate freely without imparting any rotation to the closure 56.

An outwardly flared skirt 65 is secured to the lower end of the outer surface of the post 46 and deflecting blades or vanes 66 are mounted on the skirt. The vanes 66 deflect the material outwardly and upwardly.

The post 46 also has secured thereto two sets of vanes 70 and 71 adapted to deflect the material thrown inwardly by the vanes 30 and 31 carried by the receptacle.

A discharge chute or funnel 73 is carried by the frame members 14 and 15 and is disposed beneath the discharge opening 55 of the receptacle 10.

Means is provided for rotating the receptacle 10 in either direction and driving connections are also provided for rotating the annular frame 23 in either direction. Any suitable driving connections may be utilized but in the form of the invention illustrated, there is shown a drive shaft 80 adapted for connection to any suitable source of power. A sleeve 81 is splined to the driving shaft 80 and has secured thereto a pair of gears 82 and 83. In the position of the sleeve illustrated in Fig. 1, the gear 82 meshes with a gear 85 carried by a shaft 86. The shaft 86 has secured thereto a pair of gears 87 and 88. Gear 88 meshes with the gear 26 carried by the annular frame 23. Gear 87 meshes with an idler gear 89 supported on the frame member 14, and the gear 89 meshes with the gear 25 carried by the receptacle 10.

With the driving connections in the position shown in Fig. 1, the annular frame member 23 will be driven in one direction and the receptacle will be driven in the opposite direction. Means is provided for shifting the sleeve 81 longitudinally on the shaft 80, this being accomplished by a bell crank shaft lever 90 which engages a collar 91 carried by the sleeve 81. When the sleeve is shifted downwardly on the shaft 80, the gear 82 moves out of mesh with the gear 85 and gear 83 moves into mesh with an idler gear 95, which in turn meshes with a gear 96 carried by the shaft 86. The shaft 86 will therefore be rotated in a direction opposite to the direction of rotation imparted through the gears 82 and 85.

The ring 37 has secured thereto an upwardly extending cap or casing 98 and the outer periphery of the ring is supported on rollers 99 which engage the upper surface of the flange 20 carried by the receptacle 10. 70

Operation

When the parts are in the position shown in Fig. 1, and the stop 49 is in engagement with the lug 51, the rotation of the parts by the driving connections shown in operative position in Fig. 1 will cause the receptacle to be rotated in one direction and the central cylindrical post 46 will be rotated in the opposite direction. The vanes 30, 31, 66, 70 80 and 71 will cooperate to thoroughly intermix and break up the ingredients or material within the mixer. After the mixing has been accomplished to the desired extent, the driving connections are reversed, whereupon the annular frame 23 will, by reason of the threaded engagement between the ring 37 and the threaded upper end 45 of the post 46, cause the post 46 to be moved downwardly and axially, thus opening the closure 56. 90 When the downward movement of the post has been checked by engagement of the stop lug 48 with the lug 50, the post will be rotated, this rotation being in a direction reverse to the rotation of the post during the 95 mixing operation. The inclination of the vanes carried by the post will assist in discharging the material from the receptacle.

After the material has been discharged the driving connections are again reversed and the post 46 will move axially and upwardly until the lug 49 engages the under surface of the ring 37, thus closing the opening in the bottom of the receptacle. 100

It will be obvious that the rotation of the post 46 does not effect the rotation of the closure 56 by reason of the mounting of the closure or bearings carried by the post. 105

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims. 110

What I claim is:

1. A mixer comprising a rotary receptacle, means for rotating said receptacle, means therein rotatable independently thereof and movable axially thereof, means for rotating said rotatable and axially moving means and a closure for the receptacle carried by said means. 115

2. A mixer comprising a rotary receptacle, means therein rotatable independently thereof and movable axially thereof, a closure for the receptacle carried by said means, and means carried by said rotatable means for 120

moving the material in the receptacle outwardly.

3. A mixer comprising a rotary receptacle, means therein rotatable independently thereof and movable axially thereof, a closure for the receptacle carried by said means, and means carried by said rotatable means for moving the material in the receptacle outwardly and upwardly.

10 4. A mixer comprising a rotary receptacle, a closure therefor movable bodily relative thereto, means disposed in alinement with the axis of rotation of the receptacle for moving the closure to open and closed positions, 15 said means being rotatable relative to said closure, and mixing means carried by said rotatable means.

5. A mixer comprising a rotary receptacle, a closure therefor movable bodily relative thereto, means disposed in alinement with the axis of rotation of the receptacle for moving the closure to open and closed positions, said means being rotatable relative to said closure and relative to said receptacle, and mixing 20 means carried by said rotatable means.

6. A mixer comprising a rotary receptacle, means therein rotatable independently thereof and movable axially thereof, a closure for the receptacle carried by said means, and 30 means for moving said means axially in one direction when said rotatable means is rotated in one direction and for moving said rotatable means axially in the other direction when the rotation is reversed.

35 7. A mixer comprising a rotatable receptacle, a closure therefor, reversible means in said receptacle for opening and closing said closure, and mixing means operatable by said reversible means.

40 8. A mixer comprising a rotatable receptacle, a closure therefor, and reversible means in said receptacle for opening and closing said closure, said reversible means having elements thereon for mixing the material in the 45 receptacle.

9. A mixer comprising a rotatable receptacle, a closure therefor, reversible rotatable means in said receptacle for opening and closing said closure, and mixing means oper- 50 atable by said reversible means.

10. A mixer comprising a rotatable receptacle, a closure therefor, and reversible rotatable means in said receptacle for opening and closing said closure, and blades carried by the receptacle and by said rotatable means for mixing the material in the receptacle.

11. A mixer comprising a rotatable receptacle, means for rotating the receptacle in one direction, a member disposed axially in the receptacle, reversible means for rotating said member, and a closure for the receptacle carried by said member.

12. A mixer comprising a rotatable receptacle, means for rotating the receptacle in one direction, a member disposed axially in

the receptacle, reversible means for rotating said member, a closure for the receptacle carried by said member, and blades carried by said member for deflecting and mixing the material in the receptacle.

13. A mixer comprising a rotatable receptacle, a closure therefor, reversible, rotatable and axially movable means in said receptacle for opening and closing said closure, and mixing means carried by said axially movable means.

14. A mixer comprising a receptacle, a member extending into the receptacle, a closure for the receptacle carried by the member, deflecting blades carried by said member, reversible means for rotating said member, means for moving the member axially in one direction when the member is rotated in one direction and for moving said member axially in the other direction when the member is rotated in the opposite direction.

15. A mixer comprising a rotatable receptacle, a closure therefor, axially movable means in said receptacle for opening and closing said closure, and mixing means carried by said axially movable means.

16. A mixer comprising a rotatable receptacle, means rotatable independently of said receptacle, mechanism for rotating said means, a member carried by said means and movable axially within said receptacle, and mixing means carried by said member.

17. A mixer comprising a rotatable receptacle, means rotatable independently of said receptacle, mechanism for rotating said means, a member carried by said means and movable axially within said receptacle, mixing means carried by said member, and a closure for the receptacle carried by said member.

18. A mixer comprising a rotatable receptacle, means rotatable independently of said receptacle, mechanism for rotating said means, a member carried by said means and movable axially within said receptacle, mixing means carried by said member, and a closure for the receptacle carried by said member, said member being rotatable relative to said closure.

19. A mixer comprising a rotatable receptacle, means rotatable independently of said receptacle, mechanism for rotating said means, a member carried by said means and movable axially within said receptacle, mixing means carried by said member, and means carried by said rotatable means and by said axially movable member to limit the axial movement of said member relative to said means.

20. A mixer comprising a receptacle, a closure therefor, means movable in said receptacle for opening and closing said closure, actuating means therefor, and mixing means operatable by said closure operating means.

21. A mixer comprising a receptacle, a clo-

sure therefor, rotatable means movable in said receptacle for opening and closing said closure, actuating means therefor, and mixing means operatable by said closure operating means.

22. A mixer comprising a receptacle, a closure therefor, rotatable and longitudinally movable means in said receptacle for opening and closing said closure, actuating means therefor, and mixing means operatable by said closure operating means.

23. A mixer comprising a receptacle, a closure therefor, reversibly movable means in said receptacle for opening and closing said closure, actuating means therefor, and mixing means operatable by said closure operating means.

24. A mixer comprising a receptacle, a closure therefor, means in said receptacle for opening and closing said closure, mixing means operatable by said closure operating means, and mixing means rotatable in a direction opposite to said first named mixing means.

25. In witness whereof, I have hereunto set my hand this 20th day of June, 1928.

KEMPTON ADAMS.
